C. C. TRUMP,
IGNITION CONTROL,
APPLICATION FILED DEC. 19, 1911.

1,227,979.

Patented May 29, 1917.

UNITED STATES PATENT OFFICE.

CHARLES C. TRUMP, OF SYRACUSE, NEW YORK, ASSIGNOR TO HUMPHREY GAS PUMP COMPANY, A CORPORATION OF NEW YORK.

IGNITION CONTROL.

1,227,979.

Specification of Letters Patent.

Patented May 29, 1917.

Application filed December 19, 1911. Serial No. 666,767.

To all whom it may concern:

Be it known that I, CHARLES C. TRUMP, a citizen of the United States, residing at Syracuse, in the county of Onondaga, State of New York, have invented a new and useful Ignition Control, of which the following is a specification.

My invention relates to method and means suitable for securing ignition control. My 10 object is to provide improved method and means for utilizing the flow or impact of liquid in a play pipe or combustion chamber to maintain against a restoring force an open circuit or other desired conditions either electrical or mechanical until the occurrence of a diminution, cessation or reversal of said flow whereupon said circuit is closed or other previously existing conditions restored.

20 Referring to the drawings which illustrate, by way of example, suitable apparatus for effecting my invention—

Figure 1 is a diagrammatic sectional view of an internal combustion pump employing 25 my improved means for ignition control.

Fig. 2 is a vertical section of my invention showing an open circuit condition.

Fig. 3 is a similar view showing the circuit closed.

30 Similar numerals refer to similar parts throughout the several views.

My invention is especially applicable to internal combustion engines, pumps and compressors of the general type which are 35 now known in the art as the Humphrey pump or compressor.

One of the simplest forms of such pump comprises a combustion and expansion chamber connected with the play pipe and a 40 discharge and also connected with the source of liquid supply. The operation of this device consists in expanding a compressed combustible charge in an expansion chamber against a column of liquid, thereby driving the liquid from the expansion chamber along the play pipe either to a greater head or pressure. When the momentum of the outward stroke of the liquid is spent, the column returns in the play pipe, in response 45 to the head or pressure to which it has been driven, liquid flows back into the combustion chamber to expel burnt products and to compress a fresh combustible charge which has been introduced into said chamber.

55 An igniter is intended to fire fresh combustible charges in the combustion chamber

of such a pump as above indicated in continuous operation, at precisely the proper instant of attaining a predetermined condition of volume and pressure in combination. 60 It should serve to ignite the charge at a proper time independently of the quantitative value of pressure volume or velocity of flow of liquid, and this timing should be adjustable to be either retarded or advanced. 65

Complete compression of the charge absorbs completely the energy of motion of the liquid column and brings it to rest. As the velocity approaches zero value any device which has been displaced by the impact of liquid under velocity will regain from such displacement its equilibrium. If such a device be made to close an electric circuit or otherwise produce ignition of the charge when such equilibrium is restored or as it is 70 approached, adjustably, the charge will be fired on every compression the same point of time with relation to the end or maximum pressure of compression, without regard to the absolute value of that pressure. As 75 method and means for producing this desired result I provide a Pitot tube with mercury manometer and adjustable contacts.

Referring to the drawings, the part of the tube marked 5 contains water. The part 80 marked 6 contains oil. The part marked 7 contains alcohol, while the part marked 8 contains mercury. The contacts 9 and 10 provided with the binding posts 11 and 12 are vertically adjusted through suitable 85 stuffing boxes as indicated. These two contact rods as shown in Fig. 3, are adapted to dip into the legs of the mercury column when said ends are level as shown in Fig. 3.

As above stated, upon an expansion of a 90 combustible charge the liquid, for example water, is driven from the combustion chamber 13 along the play pipe 14 toward the high level tank 15. The momentum of said moving liquid serves to entrain a fresh 95 charge and also fresh liquid. When the momentum of the outward stroke of the water is spent, the column returns in the play pipe in response to the head or pressure to which it has been driven, and liquid 100 flows back into the combustion chamber, to expel burnt products and to compress the fresh combustible charge which has been introduced into said chamber. The impact of the inmoving or rising liquid 105 at the open mouth 16 causes a displacement of the mercury column from one of the con-

acts as indicated in Fig. 2. As the velocity of the liquid moving upwardly into the expansion chamber is reduced to zero or approaches it, the mercury seeks equilibrium 5 and makes contact with both contacts 9 and 10 with a constant lead or lag, according to the adjustment of said contacts.

If a constant lead is desirable in order to compensate for the lag of slow combustion of the charges it is only necessary to lower the contacts so that a circuit is completed before the mercury reaches complete equilibrium. It is obvious that in this way any desired adjustment to meet any required 10 conditions may be secured. That is to say by the proper adjustment of the contact rods 9 and 10, it is possible to provide a completion of the circuit at any desired moment relatively to the pressure conditions of the liquid. For example, the circuit may be completed slightly before the liquid comes to rest in its instroke, so that the spark may be secured slightly in advance of the moment of maximum compression, 15 or practically simultaneous therewith, or, by a different adjustment of said rods, it may be provided that the circuit is not completed until after the liquid is compressed; thus the spark is delayed until 20 after the moment of maximum compression.

This range of adjustment makes it possible to secure the desired electrical condition at the moment most suitable to the peculiar conditions which it may be desired 25 to meet.

Copies of this patent may be obtained for five cents each, by addressing the "Commissioner of Patents, Washington, D. C."

It is obvious that the utilization of the flow or impact of liquid to affect a medium against a restoring force until the diminution, cessation or reversal of said flow, permits the restoring force to become effective, 40 may be applied to various controls, other than ignition control, which has been specifically described here, merely by way of example.

What I claim is:—

1. The method of ignition control which consists in utilizing the pressure of liquid to affect a medium against a restoring force and permitting the restoring force to become effective to react upon the medium 50 upon change of pressure of the liquid.

2. The method of utilizing the impact of liquid for controlling an electric circuit which consists in actuating a medium by said impact, against a restoring force and 55 permitting the restoring force to become effective to react upon the medium upon change of pressure of the liquid.

3. The method of utilizing the impact of liquid to make and break an electric circuit 60 which consists in actuating a medium by said impact, against a restoring force and permitting the restoring force to become effective to react upon the medium upon change of pressure of the liquid.

CHARLES C. TRUMP.
